STACKING TRAY OR THE LIKE

Charles R. Jones, St. Louis, Mo., assignor to Contico International, Inc., St. Louis, Mo.

Filed July 8, 1971, Ser. No. 160,974

Term of patent 3½ years

Int. Cl. D3—99

U.S. Cl. D87—1 R

FIG. 1

FIG. 2

FIG. 1 is a perspective view of a stacking tray or the like showing my new design;

FIG. 2 is a perspective view taken from the opposite end of the stacking tray as shown in FIG. 1; and

FIG. 3 is a bottom perspective view thereof.

I claim:

The ornamental design for a stacking tray or the like, as shown.
